UNITED STATES PATENT OFFICE

2,263,842

MEANS FOR CONNECTING CONTAINERS TO
SPRAYING DEVICESClarence Gaylord Gross, Princeville, Ill., assignor
to Binks Manufacturing Company, Chicago,
Ill., a corporation of Delaware

Application September 3, 1937, Serial No. 162,287

1 Claim. (Cl. 220—57)

The present invention relates to spray appliances, and more particularly to such types in which a hand-held spray device is detachably mounted on the cover of a so called siphon cup or pressure cup containing the material to be sprayed, such as paint or the like, so that the assemblage can be readily manipulated as a unit by the hand grasping the usual handle of the spray device.

Illustrative of the provisions commonly employed for this purpose, the Hersleb Reissue Patent #16,960 disclosed the detachable clamping of a container or cup to a cover and a paint inlet tube adapted to be attached to the usual depending material inlet of a spray gun. For this purpose, the container had to be provided with projecting lugs which afforded part of the needed clamping means, thus making it necessary to provide a separate assemblage for each of the many colors and other variations of paints and the like which many users require for small "touch-up" jobs.

The present invention aims to obviate the high cost of a large number of such specially constructed containers by providing means whereby a cover and inlet pipe assembly can readily be clamped directly to cans of a type in which a small quantities of paints are now furnished by manufacturers of paints or the like, when these cans have annular tops of certain types, thereby eliminating the need of specially constructed containers, and affording a single assemblage of a spray device with suitably designed provisions to be used interchangeably with any one of innumerable cans of different sprayable material.

Among the objects of the invention is to provide a novel means for detachably connecting a spray device having a depending inlet pipe to a spray material containing can, such as a paint can, in which the material to be sprayed is supplied, the can being of the type having an annular top in which is provided a pouring opening or mouth within the inner edge of such annular top; such novel means comprising an annular adapter detachably seated with a sealing contact with the inner edge of the annular top, together with a plurality of latching or locking members which are carried by the adapter and extend downwardly through the opening or mouth in the top of the can for latching engagement with and disengagement from the annular top mentioned, and cooperating means clamping the cover secured to the inlet pipe downwardly upon the adapter.

In the illustrative embodiment each latching or locking member comprises a shaft rotatably car-

ried by the adapter, as in a lug extending inwardly thereof, and having at its lower end a cam provided with an inclined upper surface, and a finger piece at the upper end of the shaft, as above the lug, whereby when the shaft is rotated or turned about the axis of the shaft by digitally or manually turning the finger piece, the cam is turned about such axis to bring the cam from a position beneath the opening in the can top to a position beneath the annular top where the cam bears upwardly, as with a wedging action, against the underside of the annular top of the can, to clamp the adapter down upon the inner edge of the annular top. The top of the cam may have oppositely inclined surfaces whereby either inclined surface part may be wedged against the under part of the annular top of the can from either direction of turning of the latching or locking member. The annular top of the can may be provided with an annular grooved or downwardly extending portion, V-shaped or U-shaped in cross-section, and being concentric with the inner edge of the annular top of the can, the latching or locking cams bearing upward against such grooved or downwardly extending portion. The finger piece and the cam of each latching member preferably extend laterally from the shaft and are disposed in vertical alignment so that the finger piece, which is above the lug, will serve to indicate the position of the cam relative to the annular top part of the can.

Other objects, advantages, capabilities, features, and the like are comprehended by the invention as will later appear and as are inherently possessed by the invention.

Referring to the drawing:

Fig. 1 is a perspective view of a spray device embodying the present invention for connection to a paint can, the parts being shown in separated assembly;

Fig. 2 is a vertical sectional view taken through the cover attachment, the adapter, and the upper part of a can;

Fig. 3 is a part top plan view and part horizontal sectional view taken in a plane represented by line 3—3 in Fig. 2 of the drawing;

Fig. 4 is a part top plan view and a part horizontal sectional view taken in a plane represented by line 4—4 in Fig. 2 of the drawing;

Fig. 5 is a fragmentary part bottom plan view and part horizontal sectional view taken in a plane beneath the adapter;

Fig. 6 is a vertical sectional view through the locking means including the cam and bearing boss for rotatably carrying the shaft; and

Fig. 7 is a perspective view of an alternative form of cam.

Referring more in detail to the drawing, the embodiment selected to illustrate the invention is shown in connection with a spray gun 1, comprising a body 2, having a depending handle or hand grasping part 3 provided at its lower end with a hose connection 4 for attachment to a compressed air hose. At the forward end of the body 2 is provided a spray nozzle 5 of any suitable type and at an intermediate point of the body 2 is pivotally mounted a trigger 6 cooperating with valve stems 7 and 8 suitably connected to valves for controlling the flow or passage of compressed air and material to the nozzle 5. The body 2 comprises a depending inlet 9 to which is connected a duct portion 10 by way of a suitable coupling 11. The lower part of this duct portion has threads 12 and a reduced diameter extension 13 connected by a coupling 14 to an inlet pipe 15, the lower end portion of which is bent and extends down into the can or container 16, through the opening in the top thereof.

About the duct portion 10 is slidably supported a yoke 17 having a hub 18 surrounding the pipe part 10 and adapted to have a certain amount of sliding movement thereon. The ends of the yoke 17 have depending arms 19, the lower ends of which are formed into hooks 20. To the threaded part 12 is screwed a closure or cover plate 21 having a central boss 22 against which binds the lock nut 23 for securing the cover 21 in position. The cover 21 has a depending peripheral flange 24 within which is an annular sealing gasket or ring 25. The cover 21 may be provided with an air vent 26. On the threaded portion 12 of the pipe part 10 and between the hub 18 of the yoke 17 and the central portion of the cover 21 is threadedly engaged a tightening or clamping nut 27 to which is connected an arm 28 provided at its end with an upstanding finger piece 29 by which the arm may be swung so as to turn the nut and to cause the same to press upwardly against the hub 18 and to effect a relative upward movement of the yoke 17 as will be later more fully explained.

The present invention comprehends an adapter for connecting the above described closure attachment to the upper end of a can such as can 16 referred to above. As shown, the adapter comprises a circular band or annular member 30 of hollow cylindrical form and which has at its upper edge a seat 31 adapted to have a sealing contact with the gasket or sealing ring 25, and which has at its lower edge a channel 32 in which is provided a sealing gasket or ring 33 so located as to have a sealing contact with the beaded inner edge 34 of an annular top part 35 of the can 16, this top part extending inwardly from the upper end 36 of the can or container 16. This annular top 35 comprises a downwardly extending annular portion 37, V-shaped or U-shaped in cross section, having an outer spun or lapped portion 38 secured to the upper end 36 of the can 16, and comprises inner and outer parts 39 and 40 and a bottom or trough portion 41.

Extending inwardly from the inner surface of the band 30 are provided, preferably integrally, vertically disposed lugs or bosses 42 provided with vertical bores in which are rotatably mounted shafts 43 of the locking mechanism. Each shaft comprises a shaft part 44 having squared heads 45 and 46 and a squared body portion 47. These are imbedded in a sleeve 48

5 by die casting or by forging, so that the two may operate as a single rigid unit. To the upper end of the sleeve is either rigidly connected or integrally formed the hub portion 49 of a finger piece 50 extending laterally from the axis of the shaft device. The squared body portion 47 extends below the lug or boss 42 and carries thereon a cam 51 held in place and in abutment with the lower end of the sleeve 48 by a lock nut 52 screwed upon the threaded lower end 53 of the shaft part 47. The cam is preferably provided with an inclined upper surface 54 to act with a wedging action upwardly against the lower part 41 of the annular top 35.

10 The cam may have a double wedge shape (Fig. 7) in which may be provided oppositely inclined upper surfaces 55 whereby either of such surfaces may bear upwardly against the annular top 35 in either direction of rotation of the latching device.

15 In assembling the device, the adapter is first attached to the can by placing the adapter with the gasket 33 in contact with the beaded inner edge 34 of the can top 35 and then turning the finger pieces 50 digitally or manually so as to turn the shafts with the cams 51. These cams extend laterally from the shafts and as they are turned the inclined cam face 54 will engage with the lower portion 41 of the top 35 and press upwardly against it so as to draw downwardly the band to clamp it and the gasket 33 into close sealing contact with the beaded edge 34 of the top 35.

20 In Fig. 3 the finger piece and cam are shown 35 in dotted line position when in unlocked condition, and in full line position when the same have been turned to bring the cam under and against the lower portion of the top mentioned.

25 It will also be noted that the finger pieces 40 extend vertically above the cams and preferably are in vertical alignment with a medial line of the cam radially to the axis of the shaft so that the finger pieces will serve as an indicating means of the positions of the cams relative to the top 35 with which the cams engage.

30 The closure appliance is then connected to the 45 adapter. This is effected when the nut 27 has been turned with the arm 28 to the left as viewed in Fig. 2 whereby the nut has descended upon the thread 12 so as to permit a like descent of the yoke 17. The cover 21 is placed upon the adapter 30 with the gasket 25 seated upon the seat 31 of the adapter. The appliance is then turned so as to bring the hooks 20 into engagement with radially extending lugs or trunnions 55 fixed to the outer periphery of the band 30. In this relation of the parts the trunnions 55 extend into the openings of the hooks 20. Then the arm 28 is swung to the right as viewed in Figure 2 so as to cause the nut 27 to rise on the threads 12 and to raise the hub 18 of the yoke 17, thus causing the hooks 20 to press upwardly against the trunnions 55 to cause the band 30 to press tightly against the gasket 25 and thus effect a close sealing contact. Since the cover 21 is screwed tight to the lower threaded portion 12 of the duct part 10, the cover 21 is not moved.

35 While I have herein described and upon the drawing shown an illustrative embodiment of the invention it is to be understood that the invention is not limited thereto, but comprehends other constructions, arrangements of parts, details, features, and the like, without departing from the spirit of the invention.

40 Having thus disclosed the invention,

I claim:

A container closure clamping device for clamping a closure means to the open top of a container of the type having an inwardly extending top of annular form within the inner edge of which is provided the opening for the container; comprising, in combination therewith, locking elements each of which has a shaft rotatably mounted in the closure means and extends downwardly through said opening in said top, a laterally extending cam rigid with the lower end of said shaft and having an inclined top surface portion so as to effect an upward wedging action against the underside of said annular top

when said shaft is turned to move the cam under said annular top, and a finger piece rigid with the upper end of said shaft, said annular top being provided with an annular grooved portion concentric with the inner edge of said annular top forming an annular rib on the inner face, said closure means having a downturned flange and a gasket on its inner face adjacent the flange, the closure means when in closed position having its flange and gasket in registry respectively with said groove and inner edge of the top and the cams in clamping contact with the annular rib.

CLARENCE GAYLORD GROSS.
